HEATING APPARATUS

Robert C. Belgau, Detroit, Mich.

Application August 20, 1945, Serial No. 611,462

8 Claims. (Cl. 237—67)

1

This invention relates to heating apparatus, and more particularly to heating apparatus utilizing combustible fuel as a source of heat.

One form of the invention disclosed herein comprises a boiler wherein a liquid heating medium is vaporized by the heat derived from the combustion of gaseous fuel, the vaporized heating medium being passed into heat exchange relation with the material to be heated and then returned to the boiler in a closed circulatory system.

There are many industrial processes wherein it is desired to heat a material at a rapid rate, while insuring that no part of the material is brought to a temperature which would produce burning or deterioration thereof. The requirement for accurately controlled heating means is especially stringent in the case of pharmaceutical and chemical compounds, thermo-plastic compositions, foodstuffs and similar products which deteriorate rapidly when raised to excessive temperatures.

Such materials have in the past been heated by various methods. In one known system, a central steam generating plant, utilizing coal or other fuel, supplies steam to a plurality of vessels containing the material to be heated. The temperature of the steam may in such installations be accurately controlled, so as to limit the temperature to which the material will be subjected. Such a system is wasteful and unsatisfactory in many cases, however, since it is necessary, in order to heat a single container, that the entire central plant be put into operation, with consequent fuel waste when this central system is operating on a partial load. Heat losses in conveying the steam from the central plant to the point of use may also be considerable, and the system as a whole lacks flexibility, while the original installation is costly and requires costly maintenance of the steam lines, valves, pumps and other accessories.

The present invention embodies a design which eliminates many of the objections hereinbefore pointed out, and provides a degree of flexibility and economy not possible with devices of the prior art above indicated.

An object of the present invention is to provide a heating device of simplified construction which will avoid the disadvantages of the prior art devices above outlined, in that it will be independent of other units and dependent only upon a supply of fuel at the site of heating.

A further object of the invention is to provide

2

a heating device in which a high percentage of the heat units developed by combustion of the fuel are transferred to the material to be heated.

A further object is to provide a complete vapor heating unit which may be made in any suitable size and shape, and of any suitable material, but which is complete unto itself and depends only upon a supply of fuel.

A further object of the invention is to provide 10 a heating unit utilizing heat of combustion, wherein the heating medium is circulated rapidly to avoid the formation of bubbles in the heating medium and to render the heating process more efficient.

Another object of the invention is to provide 15 a heating unit of the type indicated, wherein overrunning of the heating cycle is reduced to a minimum.

Another object of the invention is to provide 20 heating apparatus utilizing combustible fuel and automatically controlled to maintain the pressure and temperature of the vaporized heating medium within predetermined limits, wherein the automatic control operates to control separately 25 the combustion in separate systems, to minimize overrunning of the heating operation.

Further objects and advantages of the invention 30 will be apparent from the following description, taken in connection with the appended drawings, in which:

Fig. 1 is a view in vertical section of a device embodying the invention;

Fig. 2 is a vertical sectional view of the boiler and its connections;

Fig. 3 is a horizontal section taken on the line 35 3—3 of Fig. 1; and

Fig. 4 is a schematic showing of the automatic control mechanism.

It is to be understood that the invention is not 40 limited in its application to the details of construction and arrangement of parts illustrated in the accompanying drawings, since the invention is capable of other embodiments and of being 45 practiced or carried out in various ways. Also it is to be understood that the phraseology or terminology employed herein is for the purpose of description and not of limitation.

The heating apparatus shown in the drawings 50 comprises a shell of sheet metal or the like, made up of a cylindrical base section 10, a cylindrical body section 12, a frusto-conical section 14, and a stack 16. Surrounding the shell and spaced therefrom is a jacket made up of a lower section 18 and an upper section 20, the space between

the shell and jacket being sealed with heat insulating material 22.

Within the insulated chamber thus formed is mounted a boiler comprising an upper head 23 and a lower head 24, connected together by vertical tubes 28, which are secured in fluid-tight relation to the lower wall 25 of the upper head and to the upper wall 26 of the lower head in any suitable known manner, as by welding. The boiler, when in operation, is filled with liquid heating medium to a level indicated at 39, the heating medium being any suitable material such as a non-volatile oil, diethylene glycol, Dowtherm or the like, having suitable characteristics as to high boiling point, low latent heat of vaporization, and other qualities. In order to permit continuous circulation of the heating medium by thermosiphon action, return tubes 32, 33 lead from the upper head below the liquid level therein to the lower head, to permit downward flow of heating medium therein and thus balance the upward flow caused by heating of the liquid heating medium in the tubes 28.

A vapor outlet 36 leads from the upper head 23 above the liquid level therein and connects with a transverse vapor tube 38 which connects with a conduit 39 leading to the interior of a jacket 40 on a process vessel 42, adapted to contain material to be heated. Condensed heating medium from the vapor space of jacket 40 is returned to the boiler by a conduit 44, which passes through the jacket section 13 and communicates with the lower head 24, the return tube 32 being connected thereto by means of a coupling 46. A manually operated valve 48 is mounted in the conduit 39, to cut off the flow of heat to the vessel 42 when desired. A similar valve 50 is mounted in the return conduit 44, both valves being preferably of the packless diaphragm type indicated in the drawing.

The upper head 23 is suspended by brackets 52 from the tube 38, the tube in turn being suspended from the jacket by means of brackets 54. The lower head 24 is suspended from the inner shell by means of a horizontal annular plate 56, secured to the head by welding, and fitting between flanges on the base section 10 and the body section 12 of the shell. A cylindrical deflector 58 surrounds the upper portion of the tubes 28, and is suspended in any convenient manner, as by means of spaced connecting elements 60 welded thereto and to the upper head 23, the deflector being spaced by a short distance from the upper head 23 so that the deflector will not entrap lighter-than-air gases, such as producer's gas, which might be present in the apparatus because of leakage or other cause.

The tubes 28 will, in the operation of the apparatus, be filled with liquid heating medium, and will be surrounded by hot gases imparting their heat to the heating medium within the tubes. As an additional heating means for the heating medium, smaller tubes 62 are threaded through tubes 28 in concentric relation thereto, and are secured in the known manner to the upper wall 64 of the upper head 23 and to the lower wall 66 of the lower head 24. The smaller tubes are preferably of equal number with the tubes 28, and are designed to pass hot gases and transfer the heat therefrom to the heating medium in the upper and lower heads and in the tubes 28, as well as to act as staybolts for the heads. The tubes 28 and 62 are preferably spaced rather close to each other, as indicated in Fig. 3, so as to provide a rapid and economical heating action.

Beneath the lower head 24 is a horizontal wall 70 formed of heat insulating material and provided with apertures 71 which register with the smaller tubes 62. Below the wall and spaced therefrom is a second horizontal wall 72, the two being joined together by an annular insulating member 74, thus forming an annular combustion chamber 76 which communicates through the smaller tubes 62 with the chamber 78 at the upper portion of the shell. The chamber 76 is supplied with a combustible mixture through a conduit 80 provided at its outlet with an electric igniting device 81 of known type. The mixture is forced through conduit 80 by means of a centrifugal fan 82 driven by an electric motor 83, the flow of mixture being controlled by a valve 84 actuated by a solenoid 85. It will be seen that when the flow of combustible mixture is turned on and the motor started and the mixture ignited, the mixture will burn in the chamber 76 and the hot gases will pass upwardly through the tubes 62, giving up their heat to the heating medium in the boiler, and passing through chamber 78 to the stack 16.

Disposed centrally in the lower head 24 is a flue 86, within which is housed the main gas jet 88. The jet 88 is provided with an electrical igniting device 89, and is supplied through a conduit 90 with a mixture of air and combustible gas, the conduit being controlled by an automatically controlled valve 92, actuated by a solenoid 94 in the known manner. The conduit 90 and combustion chamber 76 are insulated by means of the insulating wall 72, which includes a metallic plate 96 and fibrous heat insulation 98 held in position by means of pins 100 welded to the plate 96. The space below the plate 96 is filled with heat insulation 99. It will be apparent that when a combustible mixture is permitted by the valve 92 to pass through the conduit 90 to the jet 88 and is ignited, the hot gases of combustion will pass through the flue 86 and upwardly into the space between the tubes 28, and will thence be deflected downwardly below the lower edge of deflector 58, whence they will pass upwardly to the chamber 78 and out at the stack 16.

It will be understood that instead of the gas-burning equipment just described, apparatus for burning other types of fuel, such as liquid hydrocarbons, may be used.

For automatic control of the heating process a pressurestat 101 of known type is mounted upon the upper section 18 of the jacket by means of a bracket 102. A pressure tube 104 is connected between the tube 38 and the pressurestat to communicate to the pressurestat the pressure of vaporized heating medium therein. The pressurestat contains a pressure responsive bellows 105 which is operative, upon the occurrence of pressures of a predetermined value set by adjustment of an adjusting screw 106, to open a switch, indicated at 108 in Fig. 4, in a relay circuit 112 which controls a circuit 114 leading to the solenoid 94. Upon the occurrence of a somewhat higher pressure, corresponding to a higher temperature of the vaporized heating medium, the bellows 105 will open a second switch, indicated at 110, in a second relay circuit 116 which controls a circuit 118 leading to the electric motor 83 and the solenoid 85, thus successively shutting off the supply of fuel to conduits 90 and 80. The circuits are supplied through leads 120 which are controlled by a manual switch 122.

In the operation of the device, the heating means will be put into operation by manually closing the switch 122. This will result in ener-

gizing the solenoid 94, permitting mixture to flow through the conduit 90 to the jet 88 where it will be ignited by the igniting device 89 and will supply heat to the heating medium through tubes 28 as hereinbefore indicated. Closing of the switch 122 will also cause the solenoid 85 and motor 83 to be energized, which will result in the valve 84 being opened and the gas in conduit 80 being forced into the combustion chamber 76, where it will be ignited by means of the igniting device 81. The hot products of combustion will pass from the combustion chamber 76 upwardly through the smaller tubes 62 and thence into the chamber 78 and out the stack 16. By reason of the large amount of heat transfer area represented by the tubes 28 and 62, the heating medium will be rapidly heated, causing generation of vapors in the vapor space of the head 23, which vapors will fill the conduit 38 and be superheated therein, but will be prevented from passing to the jacket 40 of the process vessel 42 by reason of valves 48 and 59 being closed. During the heating operation, heating medium will flow upwardly from the lower head 24 through the tubes 28 to the upper head 23, and thence downwardly through return tubes 32, 33 to the lower head. Such circulation is brought about by thermosiphon action in the known manner, and because of the arrangement of the parts as shown is rapid enough to break up any vapor bubbles which may form in the system, and thus to insure against the formation of bubbles in lower head 24 or in the space between tubes 28 and tubes 62, or elsewhere in the boiler, which bubbles would tend to cause burning of the tubes due to the low rate of heat transfer away from the metal adjacent such bubbles.

As the vapor in the boiler approaches the desired temperature, the valves 48 and 50 may be opened, permitting the vapor to pass through conduit 38 to the jacket 40 of the process vessel to heat the contents thereof, the condensate returning to the boiler through conduit 44. As the temperature of the vapors approaches the predetermined temperature set by adjustment of the screw 106 of the pressurestat, the bellows 105 will be actuated to cause the switch 108 to be opened, thus deenergizing the solenoid 94 and closing the valve 92. The closing of this valve cuts off the flow of combustible mixture to the gas jet 88, and thus reduces the heat intake to that supplied by conduit 80, which is of considerably less capacity than the conduit 90. Upon further increase in pressure, the bellows 105 will open the switch 110, which will deenergize the electric motor 83 and cause valve 84 to cut off the supply of gas passing through conduit 80.

By means of the apparatus above described, the rate of heating which is utilized when starting the apparatus up from cold is maintained at maximum rate until a certain pressure is reached which is slightly below that for which the screw 106 is set, then as the temperature approaches the predetermined temperature the heating rate is cut down by the closing of the valve 92, leaving the heating process to be carried on at a relatively slow rate by means of the gases burning in combustion chamber 76. Finally the supply of heat is cut off altogether by opening the switch 110, at a temperature which is still somewhat below the desired temperature of the vapors in the conduit 38. However, by reason of the residual heat in the tubes and other elements heated directly by the hot gases, heat will continue to flow to the heating medium for a short time after

the motor 83 has been stopped, so that the upper limit of temperatures within the permissible range is closely approached but not exceeded, and no burning or other damage to the material results. By this means, the heating rate may be maintained at a maximum during most of the heating cycle while "overshooting" due to hysteresis is prevented by the use of heating devices of relatively large and small capacity, and by so constructing the device that the residual heat of the boiler is small compared to that of the usual central heating system. Since in the present device the heat is generated in individual systems at the site of use, each heating apparatus or system may be of capacity sufficient merely to supply its associated vessels or other equipment, and may be started up or shut down independently of other units in the plant, and in minimum time.

Although the invention has been described with reference to a particular embodiment thereof, it may be embodied in other forms within the skill of artisans in this art. The invention is therefore not limited to the form disclosed, nor otherwise except in accordance with the language of the following claims.

I claim:

1. In heating apparatus, a boiler for vaporizable heating medium comprising upper and lower heads, tubes connecting the heads, a burner located adjacent the lower head and designed to supply hot gases to the exteriors of said tubes, a second set of tubes extending through both heads and through the first mentioned tubes, a burner for supplying hot gases to the interiors of said second mentioned tubes, said second burner including forced draft means, means responsive to a predetermined pressure in the boiler for rendering said first mentioned burner inoperative, and means responsive to a predetermined higher pressure in the boiler for rendering said second mentioned burner inoperative.

2. The invention defined in claim 1, wherein said pressure responsive means comprises a pressure responsive element and electrical circuits successively opened and closed by the pressure responsive element and operative to control the respective burners.

3. The invention defined in claim 1, wherein the pressure responsive means comprises separate valves controlling the flow of fuel to said burners, separate circuits controlling said valves, and a pressure responsive element subject to pressures in the boiler for successively opening and closing said circuits at different predetermined pressures.

4. In heating apparatus, a boiler for vaporizable heating medium comprising upper and lower heads, tubes connecting said heads, a vapor outlet conduit leading from the upper head and adapted to be connected to the point of use, a condensate return conduit leading to the lower head and adapted to return condensate from the point of use, a return conduit leading directly from the upper head to the lower head to permit circulation of heating medium therein by thermosiphon action, an insulating shell surrounding said boiler, said lower head being provided with a central aperture, a burner communicating with said aperture for supplying heated gases to said tubes, a combustion chamber beneath the lower head, tubes extending from the combustion chamber and through both heads and the first mentioned tubes, and a separately controlled burner for supplying hot gases to said combustion chamber.

5. In heating apparatus, a process vessel comprising a heating jacket, a boiler for vaporizable heating medium, conduits connecting said boiler and said jacket for conveying vaporized heating medium to the jacket and returning condensate to the boiler, said boiler comprising upper and lower heads, tubes connecting the heads and communicating therewith to permit flow of heating medium therebetween by thermo-siphon action, means including a burner of relatively large capacity for passing hot gases into contact with the exterior surfaces of said tubes, tubes extending through said heads and said first mentioned tubes and secured to said heads to act as stay-bolts for the boiler, means including a burner of relatively small capacity for passing hot gases through said second mentioned tubes, and means responsive to pressures in the boiler to separately and successively render said burners operative and inoperative.

6. The invention defined in claim 5, wherein the pressure responsive means includes separately operable valves controlling the supply of fuel to said burners, a plurality of electrical circuits controlling said valves, switches controlling said circuits, and a pressure responsive element operative by a predetermined pressure in the boiler to open one of said switches and operative upon a predetermined higher pressure in the boiler to open another of said switches.

7. The invention defined in claim 5, comprising in addition heat insulation separating said burners, a fuel conduit connected to said small ca-

pacity burner, and a valve and a compressor in said conduit, said pressure responsive means being operative to simultaneously close said valve and shut off said compressor.

5. In heating apparatus, a boiler for vaporizable heating medium comprising upper and lower heads, tubes connecting the heads, a vapor outlet conduit leading from the upper head, means for passing hot gases into contact with the exteriors 10 of said tubes and of said conduit to heat the heating medium therein, return conduits to permit flow of heating medium from the upper head to the lower head by thermo-siphon action, means responsive to pressures within the boiler for rendering the first mentioned means inoperative, and a deflector plate extending downwardly from the upper head and surrounding said tubes, said deflector plate being provided adjacent the upper head with bleed apertures to permit escape of 20 combustible gas.

ROBERT C. BELGAU.
